DETACHABLE HEEL LIFT

Benjamin H. Walker, Port Richmond,
Staten Island, N. Y.

Application March 4, 1944, Serial No. 525,015

14 Claims. (Cl. 36—42)

My invention relates to detachable lifts for the heels of shoes and particularly to an easy, simple means for unlocking and replacing the lift with another. Among the purposes and objects of my invention are to provide:

A detachable lift with a detent releasing slot.

An unlocking slot for lifts which is not easily plugged with dirt and which is in the lift or removable part rather than in the stationary part.

An unlocking slot in which no working parts are contained and which may be obstructed from movement by dirt.

A lift for she heels which may be replaced by another by the user so that the lift may be discarded when worn or replaced with one better suited to the condition of the ground or floor on which it is used, such, for instance, from leather to rubber, or to one having spikes to prevent slipping on ice.

An interchangeable lift which may be quickly removed by the wearer at low cost and without skill or tools.

A detachable lift which may be made of plastics.

I accomplish these and other objects by the construction hereinafter described and shown in the drawing forming a part hereof in which:

Fig. 1 is a side view showing the application of my device.

Fig. 2 is a bottom view of the fixed member.

Fig. 3 is a plan view of the replaceable member.

Fig. 4 is a section at 4—4, Fig. 14.

Fig. 5 is a section at 5—5, Fig. 14.

Fig. 6 is a transverse section showing a modified detent.

Fig. 7 is an elevation of the spring.

Fig. 8 is an elevation of the detent.

Fig. 9 is an elevation of the fixed member.

Fig. 10 is an elevation of the detachable member.

Fig. 11 is an elevation of the cover.

Fig. 12 is an elevation of a modified fixed member.

Fig. 13 is an elevation of the detent operator.

Fig. 14 is a bottom view of my device.

Fig. 15 is an elevation of a modified cover.

Similar reference characters refer to similar parts throughout the several views of the drawing and in the specifications to follow.

General description

Numerous detachable shoe heel lifts have been disclosed having locking means, but their construction generally is such that mud, dirt, and water render their operation impractical and de-

feats the purpose of making them removable, after a short period of use, impossible without damaging the fixed parts to which the new lift must be attached and locked in position.

By the construction of my device, a new lift may be substituted for an old one or may be temporarily changed for another for some special purpose, such as to prevent slipping on ice, for sports wear, etc.

While I have shown, for the purpose of illustration, a lift suitable for women's high heels, obviously, my device may be used for men's shoe heels, for low heels, or for any type and size of heels, such as for army shoes and for shoes suitable for heavy, rough wear, without departing from the principles underlying my invention. It is expected that after a study of this disclosure by those skilled in the art to which it pertains, modifications may be made within the scope of my invention as set forth in the claims which follow my detailed specifications; the purpose of which is to make my invention more easily understood rather than to limit the scope of my patent.

Detailed specification

Referring to the drawing, I have shown a shoe heel 1 to which the fixed member 2 is secured. The replaceable member 3 is provided with a recess 4 having overlying marginal edges 5 on three of the four sides of the recess and open on the fourth or front side to permit the member 3 to be placed over the projection 6 of the member 2 which is provided with mating overhanging companion marginal edges 7 on three sides and having the fourth or front side 8 suitable to conform to and become flush with the front side 9 of the member 3 when in place.

At about the center of the member 2 and suitable to permit free movement therein of the locking dowel 10 is the guide opening 11 which extends vertically through the member 2 from its top face 12 to the bottom face 13 of the projection 6. The dowel 10 is preferably hollow 14 and suitable to receive the coil spring 15, the bottom end 16 of which presses against the bottom closed end 17 of the dowel which is tapered or curved on the exterior at its lower end; the top end 18 of the spring 15 presses against the bottom face 19 of the heel 1 forcing the dowel downwardly through the opening 11 into the conforming recess 20 in the member 3. The lower end 17 of the dowel 10 is preferably tapered or rounded so that its periphery is above its extreme point 21 permitting an operator 22, such as a bobby

pin, hair pin, or similar small instrumentality to engage the dowel and force it, against the compression of the spring, to be raised vertically out of the recess 20.

To permit the operator 22 to engage the dowel 10, I have provided a groove 23 which is positioned in and below the face 24 of the recess 4 and extending from front to back from the front side 3 to the recess 20 and beyond to its end 25, thereby providing a portion 26 of said groove 23 back of said dowel into which the end 27 of the operator 22 may enter beyond the dowel 10. The portion 26 of the groove permits dirt or other obstacles in the groove to be forced by the operator on beyond the dowel, enabling the operator to lift the dowel after my device has been in use for long periods of time.

The number 3 may be provided with the cover piece 28 which may be of leather, rubber or other material or, as shown in the modification in Fig. 15, may be provided with irregularities 29, such as cleats, spikes, etc., attached to or formed integral with the cover 28'.

In Fig. 6, I have shown a modification in which a dowel 30 is shown having a shoulder 31 on which the end 16 of the spring may rest.

The modification shown in Fig. 12 shows a fixed member 32 having an extension 33 above the top face 34 which may project upwardly into a recess (not shown) in the heel of the shoe which may serve as a dowel or anchor for the fixed member.

Attention is called to the construction of the bottom end of the dowel 10 or 30. The tapered or curved part of the end of the dowel does not extend above the bottom face 13 of the projection 6 of 2 or the adjacent tap face 14 in the recess 4, the straight part of the dowel extends below both faces 13 and 24, thus the dowel secures the members 2 and 3 from movement unless the dowel is lifted. The dowel is not a deterrent. It must be raised by the operator which engages the curved or tapered end and thus wedges the dowel to move upwardly because of its tapered or curved end.

The groove 23 is in the member 3 and removes with it where it is exposed and easily cleaned. It may be partly filled with wax 35 at its front end to prevent dirt from entering, yet permitting the operator to force the wax into the portion 26 of the groove when lifting the dowel to remove the member 3.

The means used to secure the member 2 to the heel or the cover 28 to the member 3, when such cover is used, may be by screws, nails, cement, or any other means best suited to permanently attach these parts and this, as well as some of the other details shown, are not a part of my invention which is set forth in the claims to follow and for which I desire to secure Letters Patent.

I claim:

1. In a detachable lift for the heels of shoes having a member secured to the heel and a grooved replaceable member detachably secured thereto and locking means comprising a spring pressed dowel releasable to permit the removal of one member from the other, said groove being adapted to receive an operator insertable in said groove to move said locking means.

2. In a detachable lift for the heels of shoes having a member secured to the heel and a grooved replaceable member detachably secured thereto and locking means comprising a spring pressed dowel releasable to permit the removal

of one member from the other, said groove being adapted to receive an operator insertable therein to move said locking means and permitting said operator to be forced by and beyond said locking means.

3. In a detachable lift for the heels of shoes having a member secured to the heel and a grooved replaceable member detachably secured thereto and locking means releasable to permit the removal of one member from the other, said groove being adapted to receive an operator insertable in said groove to move said locking means, said locking means comprising a dowel with straight sides extending into said replaceable member.

4. In a detachable lift for the heels of shoes having a member secured to the heel and a grooved replaceable member detachably secured thereto and locking means releasable to permit the removal of one member from the other, said groove being adapted to receive an operator insertable in said groove to move said locking means, said locking means comprising a dowel with straight sides extending into said replaceable member, and the bottom end of said dowel formed to receive and wedge the dowel to move upwardly by engagement with said operator.

5. In a means for detaching and interchanging lifts for shoe heels, a fixed member and removable member, said fixed member having a projection and a dowel locking and preventing movement of said removable member, said removable member having a recess engaging said projection and securing both members together and a groove in the bottom of said recess and a second recess in the bottom of said recess to receive the end of said dowel between the ends of said groove.

6. In a means for detaching and interchanging lifts for shoe heels, a fixed member and removable member, said fixed member having a projection and a dowel locking and preventing movement of said removable member, said removable member having a recess engaging said projection and securing both members together and a groove in the bottom of said recess and a second recess in the bottom of said recess to receive the end of said dowel between the ends of said groove, said groove being adapted to receive an operator slideable therein for engaging the lower end of said dowel, forcing said dowel to be wedged upwardly by pressure from said operator.

7. In a means for detaching and interchanging lifts for shoe heels, a fixed member and removable member, said fixed member having a projection and a dowel locking and preventing movement of said removable member, said removable member having a recess engaging said projection and securing both members together and a groove in the bottom of said recess and a second recess in the bottom of said recess to receive the end of said dowel between the ends of said groove, said groove being adapted to receive an operator slideable therein for engaging the lower end of said dowel and causing said dowel to be wedged upwardly by pressure from said operator, and means in said removable member permitting said operator to be thrust beyond said dowel.

8. In a means for detaching and interchanging lifts for shoe heels, a fixed member and removable member, said fixed member having a projection and a dowel locking and preventing movement of said removable member, said removable member having a recess engaging said projection and securing both members together and a groove in

the bottom of said recess and a second recess in the bottom of said recess to receive the end of said dowel between the ends of said groove, said groove being adapted to receive an operator slideable therein for engaging the lower end of said dowel and causing said dowel to be wedged upwardly by pressure from said operator, said groove being open at its front end and accessible to said operator.

9. In a means for detaching and interchanging lifts for shoe heels, a fixed member and removable member, said fixed member having a projection and a dowel locking and preventing movement of said removable member, said removable member having a recess engaging said projection and securing both members together and a groove in the bottom of said recess and a second recess in the bottom of said recess to receive the end of said dowel between the ends of said groove, said groove being adapted to receive an operator slideable therein for engaging the lower end of said dowel and causing said dowel to be wedged upwardly by pressure from said operator, said groove being open at its front end and accessible to said operator, and a portion of said groove being beyond said dowel to receive dirt and the end of said operator.

10. A removable lift for shoe heels having a fixed member and a projection and dowel, a member having a recess which engages said projection to detachably hold the lift to the heel, said removable member having a groove and a recess engaging said dowel whereby said dowel is raised in said recess to permit the removal of the lift.

11. A removable lift for shoe heels having a fixed member and a projection and dowel, a member having a recess which engages said projection to detachably hold the lift to the heel, said removable member having a groove and a recess

engaging said dowel whereby said dowel is raised in said recess to permit the removal of the lift, means closing the open end of said groove.

12. A removable lift for shoe heels having a fixed member and a projection and dowel, a member having a recess which engages said projection to detachably hold the lift to the heel, said removable member having a groove and a recess engaging said dowel whereby said dowel is raised in said recess to permit the removal of the lift, means closing the open end of said groove, said groove being adapted to receive an operator to force said closing means before it along said groove.

13. A removable lift for shoe heels having a fixed member and a projection and dowel, a member having a recess which engages said projection to detachably hold the lift to the heel, said removable member having a groove and a recess engaging said dowel whereby said dowel is raised in said recess to permit the removal of the lift, means closing the open end of said groove, said groove being adapted to receive an operator to force said closing means before it along said groove, said groove having a portion beyond said dowel to receive said closing means.

14. A removable lift for shoe heels having a fixed member and a projection and dowel, a member having a recess which engages said projection to detachably hold the lift to the heel, said removable member having a groove and a recess engaging said dowel whereby said dowel is raised in said recess to permit the removal of the lift, means closing the open end of said groove, said dowel being disposed between the ends of said groove to permit said closing means to be forced beyond said dowel.

BENJAMIN H. WALKER.
